US0D1035183S

(12) **United States Design Patent** (10) **Patent No.:** **US D1,035,183 S**
(45) **Date of Patent:** **** Jul. 9, 2024**

(54) **COLLECTION TRAY**

(71) Applicants: **Jacob Joseph Fowler**, Melbourne (AU); **Kevin Herbert Fowler**, Malvern (GB)

(72) Inventors: **Jacob Joseph Fowler**, Melbourne (AU); **Kevin Herbert Fowler**, Malvern (GB)

(**) Term: **15 Years**

(21) Appl. No.: **29/847,327**

(22) Filed: **Jul. 22, 2022**

Related U.S. Application Data

(63) Continuation-in-part of application No. 29/652,828, filed on Dec. 10, 2020.

(57) **CLAIM**

The ornamental design for a collection tray, as shown and described.

DESCRIPTION

FIG. 1 is a front perspective view of a collection tray, showing my new design;

FIG. 2 is a rear perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof; and,

FIG. 7 is a bottom plan view thereof.

The broken lines showing text and a symbol in FIGS. 1–4 depict portions of the collection tray that form no part of the claimed design.

1 Claim, 5 Drawing Sheets
